UNITED STATES PATENT OFFICE.

FRANK T. LEILICH, OF BALTIMORE, MARYLAND.

SWITCH LOCK.

Application filed May 11, 1920. Serial No. 380,456.

To all whom it may concern:

Be it known that I, FRANK T. LEILICH, a citizen of the United States, residing at Baltimore, in the State of Maryland, have invented certain new and useful Improvements in Switch Locks; and I do hereby declare the following to be a full, clear, and exact description of the invention, such as will enable others skilled in the art to which it applies to make and use the same.

My invention relates to switch locks.

Among the objects of my invention are:—

To provide a simple, cheap and effective switch lock which may be used to securely lock the movable portion of an electric switch.

To provide a switch so constructed and arranged as to be capable of locking the movable portion of a switch in any position in which it contacts with the cooperating portion.

To provide a switch lock which can be operated at a distance by the use of a suitable pole.

In carrying out my invention, I make use of the instrumentalities illustrated in the accompanying drawings, in which:—

Figure 1 is a side view of a switch equipped with my improved lock.

Fig. 2 is an enlarged side view of my improved lock and the cooperating portions of the switch.

Fig. 3 is a view of the parts shown in Fig. 2 looking in the direction of the arrow 3 in said figure.

Fig. 4 is a side view of a pole for use in connection with my improved switch lock.

Fig. 5 is a view of the pole shown in Fig. 4 looking in the direction of the arrow 5 in said figure.

In the drawings:—

10 represents a structure of any approved type which serves as a support for the insulators 11 and 12. The insulator 11 carries at its upper end a hinge member 13 to which is secured one of the line terminals 14.

The insulator 12 carries at its upper end a contact 15 to which is secured the other line terminal 16.

Switch blades 17—17 are pivotally secured to the hinge member 13 by the bolt 18 and said blades closely embrace the contact 15.

The left ends of the blades 17—17 are secured together by a bolt 19 and the locking cam 20 is revolvably mounted upon said bolt. The cam 20 is provided with a plurality of

dentations as at 21 which co-act with the dentations 22 upon the contact 15 to lock the switch as hereinafter explained.

The pin 23 extending between the blades 17—17 serves to limit the rotation of the cam 20 in a counter-clockwise direction.

The spring 24 is secured to the pin 25 and the latter is secured in the blades 17—17 in any approved manner. The spring 24 is prevented from moving in a clockwise direction by the pin 26 which is secured in the blades 17—17 in any approved manner and the end of said spring is mounted in the notch 27 formed in the cam 20. Thus, the force of said spring presses the dentations 21 against the dentations 22.

The switch blades 17—17 are each provided with a slot having rounded ends such as 28, and the cam 20 is provided with a slot 29 having one round end and one straight end.

The pole 30 is provided with an end 31 of any approved form and said end has a key portion 32 shaped as shown in Fig 5 to fit the slot 29 in the cam 20.

The operation of my improved switch is as follows:—

When the parts are as shown in Figs. 1 and 2, the dentations 21 engage the dentations 22, and should any force act to move the blades in a counter-clockwise direction about the bolt 18, this force will be resisted by the interaction of said dentations, thus locking the switch blades in the position shown in said figures.

When it is desired to open the circuit, the operator introduces the key portion 32 within the slot 29 of the cam 20 and moves the pole 30 upwardly, thus moving the dentations 21 from the dentations 22 and the further motion of the key portion 32 brings it into contact with the slot 28 after which the further upward motion of the pole 30 moves the switch blades 17—17 in a counter-clockwise direction upon the bolt 18, thus opening the circuit.

When it is desired to close the circuit, the switch blades 17—17 are moved in a clockwise direction in any manner and brought into contact with the contact 15. During this motion the dentations 21 will strike the dentations 22 and slide along same without interfering with the clockwise motion of said blades. Thus, it will be noted that my improved lock locks the blades 17—17 at any position with reference to the contact 15.

after the dentations 21 come in contact with the dentations 22.

By this construction, I am enabled to provide a switch lock which locks the blades even though the latter are not moved to a pre-determined position, and thus avoids the objection heretofore existing to switch locks in that the latter failed to lock the switch blade unless it was moved to a certain position.

While I have shown one embodiment of my improved switch, it is to be noted that many changes may be made therein without departing from the spirit of my invention. As for instance, the dentations 21 and 22 may be omitted and various changes may be made in the fixed and movable contact makers.

I claim:—

1. In a switch lock, the combination with a movable contact maker and a fixed contact, of a cam on said maker located to engage said fixed contact at any one of a plurality of positions of said maker and prevent movement of said maker with reference to said fixed contact.

2. In a switch lock, the combination with a movable contact maker and a fixed contact, of a cam on said maker located to engage said fixed contact at any one of a plurality of positions of said maker and prevent movement of said maker with reference to said fixed contact towards the open circuit position.

3. In a switch lock, the combination with a movable contact maker and a fixed contact, of a cam pivotally mounted on said maker and engaging said contact at any one of a plurality of positions of said maker and a spring for pressing said cam against said fixed contact.

4. In a switch lock, the combination with a movable contact maker and a fixed contact, of a cam pivotally mounted on said maker, a spring for pressing said cam against said fixed contact, and mutually engaging dentations on said cam and said fixed contact for locking said maker in any one of a plurality of positions.

In testimony whereof, I affix my signature.

FRANK T. LEILICH.
